UNITED STATES PATENT OFFICE.

BEATRICE PIAZZONI, OF SAN FRANCISCO, CALIFORNIA.

HAIR WAVER.

Application filed August 24, 1927. Serial No. 215,166.

This invention resides in the provision of a hair waver which is simple as to construction, inexpensive, exceptionally small and compact, and ornamental and which may 5 be quickly and easily applied to the hair to produce lasting waves of the desired form.

One of the objects of the invention is to provide a hair waver of the character described which waver will permit of a quick 10 hair waving operation with a heated iron, tongs or other similar appliance, without burning the hair, or without the use of a heated iron or other waving appliance will also provide for an expeditious waving of 15 the hair.

A further object is to provide a hair waver which will not discomfort the user due to its shape, flexibility and special construction, said waver being inconspicuous when 20 in use.

With the above mentioned and other objects in view, the invention consists in the novel construction and combination of parts hereinafter described, illustrated in the accompanying drawing, and set forth in the claims hereto appended, it being understood that various changes in the form, proportion, size and minor details of construction within the scope of the claims may be resorted 25 to without departing from the spirit or sacrificing any of the advantages of the invention.

Referring to the drawing:

Fig. 1 is a top plan view of the hair waver 25 as when open.

Fig. 2 is a top plan view of the hair waver as when closed.

Fig. 3 is an edge view in elevation of the hair waver as when closed.

Fig. 4 is a side elevation of the hair waver showing the manner of applying heating tongs thereto.

One embodiment of my invention which is shown in detail in the accompanying drawing is made up of two thin and comparatively small foraminated metal pieces 1 and 2, preferably of disk or sheet form and hinged as at 3, said disks being adapted to be clamped together with the hair to 50 be waved pressed between them. A clasp is provided and in the present instance it comprises a bendable peripheral projection 4 on each of the disks. I prefer to make the disks circular and of small resilient and bendable wire woven in a spider web mesh and

about an inch and one half in diameter but I wish it understood that the disks may be made of any suitable material and of varying sizes and shapes and not necessarily in spider web mesh. However, by using spider 60 web meshed metal disks which are circular and about the size of a silver half dollar, I provide an inexpensive and most effective waver which is small, compact, easy to operate and highly ornamental. Because of 65 the small wire the disks are made bendable and resilient and therefore will not discomfort the user. The wire will become heated when a heated curling iron or like device is applied thereto and will expedite the application of heat to the hair to be waved. The 70 shape and construction of the disks provide for an effective application of heating irons or tongs to the waver without burning the hair.

To use the waver, the hair to be waved is convolved around the finger or other object and when in the desired form is placed between the disks 1 and 2, which disks are then pressed together to clamp the hair tightly 80 between them. The bendable projections 4 are then bent over and upon the outer side of the disks and thereby hold the disks together. The hair may be dampened either before or after being placed in the waver. 85

On removing the waver from the hair after it has remained in place for the usual length of time, the hair will be found to be effectively waved as desired. To produce a quick wave, heated irons or tongs are applied to the waver 90 which itself becomes heated and facilitates the application of heat to the hair. The irregularities provided by a spider web weave insures a tight and effective clamping of the hair between the disks and also facilitates the holding of the iron or tongs on the waver 95 besides rendering the article as a whole exceptionally ornamental. The spider web weave also provides for use of fine wire and makes for a small, light, inconspicuous device in that said weave provides more rigidity and strength than ordinary square mesh weaves. However, the main advantages of my invention may be secured by use of thin, pliable, foraminated disks arranged so that 100 they may be readily clasped together with the hair therebetween, the said disks being preferably but not necessarily made of wire.

It will be noted that the border of each disk is provided by several small wires twist- 110

ed one around the other whereas the body portion is composed of single wires woven to provide the desired mesh, in this instance, a spider web weave being used. This makes 5 the body portion readily pliable while giving the necessary rigidity and strength to make the device durable.

Another advantage of the waver of this invention is that it can be sterilized after 10 each use without injury to the device.

I claim:

1. A hair waver comprising a pair of

meshed wire disks adapted to hold hair between them and means for clamping the disks together.

2. A hair waver comprising two bendable meshed wire disks hinged together and adapted to fold together to clamp between them the hair to be waved, and a bendable clasp on one disk adapted to be bent over 20 and upon the other disk to hold the disks closely together.

BEATRICE PIAZZONI.
